UNITED STATES PATENT OFFICE

172,830

GAME BOARD

Pharis S. Hebert, Santa Rosa, Calif.

Application February 23, 1954, Serial No. 29,151

Term of patent 14 years

(Cl. D34—5)

To all whom it may concern:

Be it known that I, Pharis S. Hebert, a citizen of the United States, residing at Santa Rosa, in the county of Sonoma and State of California, have invented a new, original, and ornamental Design for a Game Board, of which the following is a specification, reference being had to the drawing, forming a part thereof.

Fig. 1 is a top plan view of a game board showing my new design, the side opposite that being substantially plain.

Fig. 2 is a side elevation as viewed from the near side of Fig. 1, the opposite side being similar in appearance.

Fig. 3 is a side elevation as viewed at ninety degrees to Fig. 2, the opposite side being similar in appearance.

I claim:

The ornamental design for a game board, as shown and described.
